JEWELRY CLASP OR CONNECTOR

Arthur H. Levesque, North Attleboro, Mass., assignor to R. F. Simmons Company, Attleboro, Mass., a partnership consisting of Harold E. Sweet and Hayward H. Sweet

Application January 28, 1939, Serial No. 253,361

8 Claims. (Cl. 24—241)

The present invention relates to jewelry clasps and more particularly to clasps for attaching the ends of straps, bands or bracelets to wrist-watch bails or the like.

5 One of the objects of the present invention is to provide a clasp of the type indicated adapted to be easily and quickly attached to and detached from the bail of a wrist-watch while preventing its accidental detachment therefrom during use. 10 Another object of the invention is to provide a clasp of the type indicated having means for attaching the end of a strap, band or bracelet thereto and a pivoted hook adapted to be looped through the bail or eye on the wrist-watch to 15 connect the clasp to the watch.

Another object of the invention is to provide a clasp of the type indicated having a latching member mounted to rock on the clasp about an axis at right-angles to the pivotal axis of the 20 hook and adapted to interlock with the free end of the hook to retain the latter in closed position on the clasp.

Another object of the invention is to provide a clasp of the type indicated wherein the pivoted 25 latching member has a top and side walls which cooperate with the top and side walls of the body-member of the clasp to provide a smooth continuous surface therewith.

Further objects of the invention are set forth 30 in the following specification which describes a preferred embodiment of the invention, by way of example, as illustrated in the accompanying drawing. In the drawing:

Fig. 1 is a view showing a lady's wrist-watch of 35 conventional type connected to the ends of a two-part bracelet by means of improved clasps embodying the subject-matter of the present invention;

Fig. 2 is an enlarged plan view of one of the 40 clasps illustrated in Fig. 1 showing the hook locked in closed position on the body-member of the clasp;

Fig. 3 is a view similar to Fig. 2 showing the latching member swung on its pivot to release 45 the end of the hook;

Fig. 4 is a view similar to Fig. 3 showing the hook swung to open position to release the bail on the watch;

Fig. 5 is a side view of the clasp showing the 50 latching member in closed position on the body-member;

Fig. 6 is a longitudinal sectional view of the clasp illustrated with the latching member swung upwardly on its pivot to release the end of the 55 hook and showing the retaining or clamping

means for attaching the bracelet end to the clasp;

Fig. 7 is a transverse sectional view taken on line 7—7 of Fig. 2 showing the detent-means on the latching member in engagement with one of the flanges on the body-member to retain it in closed position thereon;

Fig. 8 is a transverse sectional view taken on line 8—8 of Fig. 2 showing the common pivot-pin for mounting the clamping member and 10 latching member; and

Fig. 9 is a perspective view of the several parts of the clasp shown in disassembled relationship.

Referring to the present drawing, Fig. 1 illustrates a lady's wrist-watch 2 having loop-like ears or bails 3 at its sides to which the ends of the two parts 4 and 5 of the bracelet are connected by means of the present improved clasps 6. As illustrated in the drawing the bracelet parts 4 and 5 are in the form of looped cords, but it 20 will be understood that the clasps 6 may be used with any other type of band, strap, bracelet or the like.

The two clasps 6 are of identical construction, each comprising a hollow body-member 10 having a top wall 11 of a shape to conform to the contour of the bracelet cords 4 or 5 and depending side walls 12 and 13. The side walls 12 and 15 are stepped inwardly intermediate their ends to provide offset portions 14 and 15 with vertical 25 shoulders 16 therebetween. Forwardly of the shoulders 16 the top wall 11 is stepped downwardly to provide an offset parallel portion 17 with a perpendicular shoulder 18 therebetween, see Fig. 9.

The forwardly projecting offset portion 17 30 of the body-member 10 is slotted transversely at 21 to form spaced horizontal flanges 19 and 20. The flanges 19 and 20 are pierced with aligned holes 22 adjacent one of their outer corners and the opposite corners are cut away to provide 40 aligned recesses or slots 23. The opposite end of the body-member 10 is provided with lugs 24 projecting inwardly toward each other from the lower edges of the side walls 12 and 13.

The ends of a bracelet cord 4 or 5 are inserted 45 into the body-member 10 through its open bottom and are clamped thereto by a retaining member 25. The retaining member 25 may be in the form of a clamping lever pivotally mounted at one end on a transverse pin 26 extending between the side walls 12 and 13 of the body-member 10 and having a toothed jaw 27 at its opposite end for engagement with the end of the bracelet. As illustrated in Fig. 6, the sides of the retaining member 25 adjacent the jaw 27 are adapted to 50 55

snap past the ends of the inwardly-projecting lugs 26 on the side walls 12 and 13 of the body-member 10 which act to hold the retaining member in clamped engagement with the end of the bracelet cord 4 or 5. The retaining member 25 also serves to close the open bottom of the body-member 10 when swung into closed position thereon.

In accordance with the present invention a hook 30 is provided on the body-member 10 for connecting it to the wrist-watch 2 or the like. The hook 30 is preferably of U-shape in plan view, and of a thickness to adapt it to closely fit within the opening or slot 21 between the spaced flanges 19 and 20 on the body-member 10. The hook 30 is formed with opposite parallel legs 31 and 32 so spaced that their outside faces form a continuation of the offset portions 14 and 15 of the sides 12 and 13 of the body-member 10. The end of one leg 31 is formed to provide a hub-like bearing 33 having a central bore 34, while the outside face of the opposite leg 32 adjacent its end is slotted transversely to provide a latching recess 35. The end of the leg 31 of the hook 30 having the bearing 33 is positioned between the flanges 19 and 20 and pivoted thereto by means of a pin 36 extending through the aligned holes 22 and 34 in the flanges and bearing. Thus, the hook 30 is adapted to be rocked on its pivot-pin 36 from the position shown in Fig. 3 to that shown in Fig. 4, or vice-versa.

A latching member 40 is pivotally mounted on the laterally-projecting ends of the pin 26, previously described, to adapt it to rock about an axis at right-angles to the pivotal axis of the hook 30. The latching member 40, see Fig. 9, has a top wall 41 and depending side walls 42 and 43 so constructed and arranged as to overlie the offset portion 17 of the top wall 11 and the portions 14 and 15 of the side walls 12 and 13 of the body-member 10 with a close fit; the top wall 41 and side walls 42 and 43 of the latching member extending outwardly to the ends of the flanges 19 and 20. The stepped portions 14, 15 and 17 of the body-member 10 are offset or recessed to an extent equal to the thickness of the metal of the latching member 40 so that the outside faces of the latter form a smooth continuation of the top and sides of the body-member when said member 40 is in closed position thereon. An inwardly-bent flange 45 at the end of the side wall 43 of the latching member 40 is adapted to enter the aligned slots or recesses 23 in the flanges 19, 20 of the body-member 10 and in the slot 35 in the side of the leg 32 of the hook 30. A detent projection 46 is provided on the inner side wall 42 of the latching member 40 adapted to cooperate with the under edge of the flange 19, see Fig. 7, to retain the latching member in closed position on the body-member 10. One form of construction of the clasp having now been described in detail its mode of operation is as next explained.

The end of the bracelet 4 or 5 is first inserted into the body-member 10 through its open bottom and attached thereto by rocking the retaining member or clamp 25 on its pivot-pin 26 to engage its toothed jaw 27 with the cords. The engagement of the ends of the lugs 24 on the body-member 10 with the sides of the retaining member 25 adjacent the jaw 27 holds the jaw in clamped engagement with the cord. The hook 30 in its open position illustrated in Fig. 4 is looped through one of the bails or eyes 3 at the side of the wrist-watch 2 and swung on its pivot-

pin 36 to position the free end of its leg 32 in the slot or opening 21 between the spaced flanges 19 and 20 of the body-member 10. With the hook 30 in this closed position its latching recess 35 will align with the recesses 23 at the corners of the flanges 19 and 20. The latching member 40 is next swung on its pivot-pin 26 to cause its side walls 42 and 43 to overlie the sides of the hook 30. During the rocking movement of the latching member 40 its flange 45 will enter the aligned recesses 23 in the flanges 19, 20 and engage the slot 35 in the hook 30 to positively lock the free end of the hook to the body-member 10. As the top wall 41 of the latching member 40 is seated against the top of the flange 19 the detent 46 in its side wall 42 will engage under the bottom edge of the flange to retain the latching member in closed position on the body-member. Thus, it will be noted that the hook 30 forms a closed loop at the end of the body-member 10 embracing the bail 3 of the wrist-watch 2, and due to the locking engagement of the flange 45 in the slot 35 in the hook the clasp 6 is securely attached to the watch 2. The clasp 6 may be detached from the bail 3 of the watch 2 by rocking the latching member 40 to the position shown in Fig. 6 to disengage its flange 45 from the slot 35 in the hook 30. The hook 30 may then be swung on its pivot-pin 36 to the position shown in Fig. 4 to release the bail 3 of the wrist-watch 2.

It will be observed from the foregoing that the present invention provides a clasp device for securely attaching a bracelet to a wrist-watch to guard against its accidental detachment therefrom. It will also be observed that the invention provides a clasp device having a hook rockable to closed position and a latching member rockable about an axis at right-angles to the pivotal axis of the hook whereby any force applied to rock the hook to open position has no tendency to release the latching member. Still further, it will be observed that the present improved clasp device is of comparatively simple construction to adapt it for economical manufacture while having a pleasing and ornamental appearance.

While I have herein shown a preferred form of construction of the clasp by way of example, it is to be understood that modifications may be made in the structure and arrangement of its parts without departing from the spirit or scope of the invention.

Therefore, without limiting myself in this respect, I claim:

1. A clasp comprising a body-member for attachment to the end of a bracelet or the like, a substantially U-shaped hook hinged to the end of the body-member to adapt it to swing laterally of the body-member into open position and to swing in the opposite direction to close its open end against the body-member, and a latching member pivoted to the body-member to swing in a plane at right-angles to the plane of movement of the hook and so constructed and arranged as to adapt it to engage against the side of the hook to hold the latter in closed position.

2. A clasp comprising a body-member, a substantially U-shaped hook having one leg hinged to the end of the body-member to adapt it to swing to carry its free leg away therefrom or to swing in the opposite direction to close the end of its free leg thereagainst, and a latching member pivoted to the body-member to swing across the plane of movement of the hook and so constructed and arranged as to adapt it to slide

- across the side of the hook when the latter is in closed position to retain it against opening.
3. A clasp comprising a body-member having spaced flanges at one end, a pin extending between said flanges, a substantially U-shaped hook having one leg pivotally mounted on said pin to adapt its opposite leg to swing into the opening between the flanges, and a latching member mounted on the body-member to rock about an axis at right-angles to the pivotal axis of the hook to overlie the side of the free end of the hook to latch it in closed position.
4. A clasp comprising a body-member having spaced flanges at one end, a pin extending between said flanges, a U-shaped hook having one leg pivotally mounted on said pin to adapt its opposite leg to swing into the opening between the flanges, and a latching member mounted on the body-member to rock about an axis at right-angles to the pivotal axis of the hook and having side walls overlying the sides of the hook.
5. A clasp comprising a hollow body-member for receiving the end of a bracelet or the like, means for clamping the end of the bracelet therein, a hook having one end hingedly connected to one end of the body-member and a loop-portion projecting outwardly therefrom, said hook being rockable on the body-member to swing its free end away from the body-member into open position or to swing toward the body-member adjacent the end thereof into closed position, and a latching member hingedly mounted on the body-member to rock about an axis at right-angles to the axis on which the hook is hinged to overlie the side of the free end of the latter to latch it in closed position.
6. A clasp comprising a hollow body-member for receiving the end of a bracelet or the like, means for clamping the end of the bracelet therein, a substantially U-shaped hook having one end hingedly mounted on the body-member and a loop-portion projecting outwardly therefrom, said hook being rockable on the body-member to swing its free end away from the body-member into

open position or to swing toward the body-member adjacent the end thereof into closed position, and a channel-shaped cover-member hingedly mounted on the body-member to rock about an axis at right-angles to the axis on which the hook is hinged to overlie the sides of the hook to latch it in closed position.

7. A clasp comprising a hollow body-member adapted for receiving the end of a bracelet or the like and having spaced flanges at one end, means for clamping the end of the bracelet therein, a pin extending between said flanges, a U-shaped hook having one end hingedly mounted on said pin and a loop-portion projecting outwardly from the body-member, said hook being rockable on said pin to swing its free end away from the body-member into open position or to swing toward the body-member adjacent the side thereof into closed position, and a channel-shaped cover-member hingedly mounted on the body-member to swing about an axis at right-angles to the axis of the pin to overlie the sides of the hook to latch it in closed position.

8. A clasp for attaching the end of a bracelet to the bail of a wrist-watch comprising a hollow body-member for receiving the end of a bracelet and spaced flanges projecting from one end thereof, said flanges having aligned recesses at one edge thereof, a pin extending between the flanges, a pivoted jaw for attaching the end of the bracelet to the body-member, a U-shaped hook having one end pivotally mounted on the pin to adapt its opposite free end to swing into the opening between the flanges, said hook having a transverse slot adjacent its free end adapted to align with the recesses on the sides of the flanges, and a latching member pivoted at one end to the body-member to adapt it to rock about an axis at right-angles to the pivotal axis of the hook and having a projection engageable with the aligned recesses and slot in the flanges and hook to latch the latter to the body-member.

ARTHUR H. LEVESQUE.
